FEEDING MECHANISM FOR DRUM-TYPE FIREARM

Joseph L. Johnston, Hartland, Wis., and Anders G. Pettersson, Fraser, Mich., assignors, by mesne assignments, to the United States of America as represented by the Secretary of the Army

Filed Nov. 4, 1960, Ser. No. 67,445
5 Claims. (Cl. 89—33)

This invention relates to machine guns of revolver type and more particularly to the feeding mechanisms thereof.

It is an object of this invention to provide for machine guns of revolver type a feeding mechanism having a housing which is symmetrical in transversal cross-section so that feed may be changed from one side thereof to the other only by interchanging the entrance, link and case chutes.

It is another object of this invention to provide for such guns a feeding mechanism having a housing which is open at the top with such opening being closed by a replaceable cover to facilitate the loading of the cartridge belt to the feeding mechanism and to make the interior readily accessible in event of any malfunction thereof.

It is a further object of this invention to provide for such guns a feeding mechanism in which the rammer is carried and guided by the replaceable cover and is symmetrically disposed therein respective to the central vertical plane of the gun and is adapted to ram the cartridges from the belt into the gun drum at the one and eleven o'clock positions to provide a symmetrical distribution of the ramming forces.

It is still another object of this invention to provide such a rammer which is connected to the operating slide of the gun for reciprocation therewith and which is stopped at the forward position thereof by contact with the rear face of the drum to prevent an overramming of the chambered cartridge which would space the cartridge primer from the firing pin and so could not be discharged.

It is another and still further object of this invention to provide for such a feeding mechanism a buffer operationally disposed so as to cushion the impact between the rammer and drum and thereby reduce counterrecoil forces produced by operating slide impact as it goes into battery position.

The specific nature of the invention as well as other objects and advantages thereof will clearly appear from a description of a preferred embodiment as shown in the accompanying drawings in which:

FIG. 1 is a perspective, exploded view of the revolver-type gun of this invention;

FIG. 2 is a longitudinally cross-sectioned side view of the feeding mechanism and drum of the gun;

FIG. 3 is a forward extension of FIG. 2;

FIG. 4 is a view taken along line 4—4 of FIG. 2;

FIG. 5 is a perspective, exploded view of the feeding mechanism;

FIG. 6 is a view taken along line 6—6 of FIG. 2;

FIG. 7 is a view taken along line 7—7 of FIG. 6;

FIG. 8 is a view taken along line 8—8 of FIG. 7;

FIG. 9 is a view taken along line 9—9 of FIG. 6 showing the rammer in the battery position; and

FIG. 10 is a view similar to FIG. 9 but showing the rammer in the recoil position.

Shown in the figures is a revolver-type machine gun 12 which includes a mount 14 for attaching the rear end of the gun to a supporting structure 16. Mount 14 includes a bracket 18 for securing the mount to structure 16 so as to be immovable respective thereto. A pair of laterally spaced and longitudinally disposed rods 20 are immediately secured by bracket 18 so as to extend both for-

2

wardly and rearwardly therefrom. A feeding mechanism 22 is mounted on the rearwardly extending sections of the rods 20 so as to be immovable respective thereto. The remaining portion of gun 12, comprising the recoil mass thereof, is slidably mounted on the forwardly extending sections of the rods. Whereby, feeding mechanism 22 is isolated from the recoil mass of gun 12 and is stationary relative to structure 16.

The recoil mass of gun 12 includes a drum cradle 24 which rotatably supports a drum 26 by means of a longitudinally disposed shaft 28. A barrel 30 is replaceably mounted to the front end of a carriage 31 which is fixedly secured to cradle 24. Drum 26 is provided with five symmetrically disposed chambers 32 which respectively receive a cartridge 34 for discharge therein. Chambers 32 are disposed in drum 26 so as to be successively alignable with a bore 35 in barrel 30 when coincidental with the central vertical plane of gun 12, noted at X—X, in FIG. 4 during the bottom portion of the rotational cycle of the drum. Such position is known in the art as the six o'clock position and will be referred to as such herein-after. It is at this six o'clock position that the cartridges 34 are discharged by a firing pin 37. When drum 26 is in battery, with one of the chambers 32 indexed at the six o'clock position, the two chambers opposite that in the six o'clock position are disposed on opposite sides of central vertical plane X—X. The one of such chambers 32 which is disposed on the right side of central vertical plane X—X, looking forwardly from the rear end of the gun, is in a position which will be referred to as the one o'clock position while the chamber on the left side is in a position which will be referred to as the eleven o'clock position.

Carriage 31 is provided with an integral pair of longitudinally disposed and laterally spaced tubes 36 which slidably receive the forwardly extending sections of the rods 20 to slidably mount cradle 24 to mount 14. Each of the tubes 36 encases a buffer device (not shown) which is operationally interposed between the respective tubes and rods 20 for absorbing a portion of the recoil forces produced in the recoil mass of gun 12 when a cartridge 34 is discharged in drum 26. The forward end of gun 12 is supported by a sleeve 40 which is fixed to supporting structure 16 and which slidably receives a bearing section 42 formed at the front end of a cradle extension 44 which extends forwardly from the front end of cradle 24. Whereby, the recoil mass of gun 12 is disposed for longitudinal reciprocation respective to supporting structure 16.

Drum 26 is rotated to successively index chambers 32 at the six o'clock position by an operating slide 46 which is disposed in the top of cradle 24 for longitudinal reciprocation between a recoil and a battery position. Operating slide 46 is energized for movement to the recoil position by a piston 48 which is received by a co-operating cylinder 50 having communication with bore 35. A pair of operating springs 52 are positioned between the front end of cradle 24 and operating slide 46 so as to be energized during the recoil stroke thereof for returning the operating slide to the battery position. The translational recoil stroke of operating slide 46 is converted to a counterclockwise rotation of drum 26, for successively indexing the chambers 32 at the six o'clock position, by a cam track 54 which is disposed in the operating slide for cooperation with five followers 56 extending radially from the outside perimeter of the drum.

Feeding mechanism 22 includes a housing 58 which has a symmetrical configuration in transversal cross-section so that a cartridge belt 60 may be fed to gun 12 from either the right or left side thereof without a change of housings. As best shown in FIG. 6, cartridge belt 60 includes a plurality of connected links 62 which are de-

signed for gripping the cartridges 34 so as to permit longitudinal stripping therefrom.

A pair of bores 64 extend longitudinally through the base of housing 58 for receiving the rearwardly extending portions of the rods 20 and the housing is secured thereto by ball lock pins 66 so that feeding mechanism is held stationary respective to mount 14 and, therefore to supporting structure 16.

Housing 58 rotatably supports a sprocket-wheel cluster 68 which is axially aligned to drum 26 and is coupled to shaft 28 for rotation thereby. Cluster 68 includes a cylindrical hub 69 on which there is provided a front sprocket-wheel 70 and a rear sprocket-wheel 72 of similar diameter with a center sprocket-wheel 74 of smaller diameter disposed therebetween. Cluster 68 is of five-sprocket type with the sprockets forming therebetween five semi-circular pockets 76 which are spaced to receive successive ones of the cartridges 34 and the associated gripping links 62 and which are each aligned with one of the chambers 32. Front sprocket-wheel 70 is disposed for engagement with the front sections of the links 62 and rear sprocket wheel 72 with the rear sections thereof while center sprocket-wheel 74 engages the central section.

Housing 58 is open at the top and such opening is closed by a cover 78 which is replaceably secured to the housing by four ball-lock pins 80 so that cluster 68 is readily accessible in event of a malfunction of the feeding system thereat and installation of belt 60 is facilitated.

An entrance chute 82 is mounted to the right side of housing 58 for directing belt 60 thereto over cluster 68 for engagement thereby. A track 84 is formed along the base of entrance chute so as to be slidably engaged by tabs 85 (FIG. 7) formed on the backs of the links 62 for holding the links against longitudinal displacement, respective to gun 12, when the cartridges 34 are stripped therefrom as hereinafter explained. The base of entrance chute 82 with track 84 extends sufficiently over cluster 68 so that the tabs 85 on the link 62 which grip the cartridge 34 disposed at the one o'clock position are engaged in the track. Clearances are provided in the base of entrance chute 82 to permit the extension of cluster 68 upwardly therethrough to engage belt 60. Thereby, the base of entrance chute 82 makes contact with hub 69 so that the centerline of links 62 in entrance chute 82 is tangent to the pitch circles of the drum chambers. Entrance chute 82 is cut away above the base thereof at the forward end to provide a clearance 86 for the longitudinal displacement of the eleven o'clock position cartridge 34 towards the aligned one of the chambers 32.

Also mounted to the right side of housing 58 is a link ejection chute 88 which maintains the engagement of links 62 with center sprocket-wheel 74, after the cartridges 34 are stripped therefrom, and directs the links out of housing 58 below entrance chute 82. A cartridge case ejection tube 92 extends longitudinally through housing 58 and is disposed therein so as to be in registry with the one of the chambers 32 which, when drum 26 is in battery, is indexed in the position which is between the one and six o'clock positions and which will be referred to as the ejection position. The front end of case ejection tube 92 is enlarged to an eccentric funnel configuration so as to be in registry with the ejection position chamber 32 while the rear section of the tube is offset to pass between entrance chute 82 and link ejection chute 88 clear of cluster 68 as best shown in FIG. 6.

Because housing 58 is symmetrical in transversal cross-section, gun 12 may be changed from one hand feed to the other, with the only changes to be made to the housing being in the interchange of entrance chute 82, link ejection chute 88 and case ejection tube 92 to the opposite sides of the housing.

Cartridges 34 are successively stripped from belt 60 and chambered in drum 26 by a rammer 96 which is assembled within cover 78. Rammer 96 is supported for

longitudinal reciprocation in cover 78 between a pair of longitudinally disposed and laterally spaced rails 98 which are symmetrically fixed to the cover on the inside thereof for sliding engagement by mating grooves 100 in the rammer. Thus, rammer 96 is carried by feeding mechanism 22 and is removed therefrom along with cover 78 after release from slide 46.

Rammer 96 is connected to operating slide 46 for reciprocation therewith by a shaft 102 which extends longitudinally forward from the rammer and is joined to the operating slide by a transversely disposed pin 104. Shaft 102 extends slidably through a bore 106 in a boss 108 centrally disposed on the top of rammer 96. Bore 106 is counterbored from the front end to form an annular shoulder 110 which is contactable by an annular flange 112 on shaft 102 for transferring the recoil movement of operating slide 46 to rammer 96. Shaft 102 extends rearwardly beyond boss 108 and is provided with a threaded section at the rear end for threadingly mounting a nut 114 which is backed by a washer 116. A coil spring 118 is mounted on the rearwardly extending section of shaft 102 between washer 116 and boss 108 and is pre-loaded to resiliently hold flange 112 in contact with shoulder 110 and so interpose a buffer between rammer 96 and operating slide 46.

Rammer 96 includes a first ram 120 which depends therefrom for contact with the base of cartridge 34 indexed at the one o'clock position so as to strip such cartridge from the associated link 62 and position it partially within the aligned one of the chambers 32 during forward displacement of the rammer. In order to prevent eccentric ramming forces which would tend to force the rammed cartridges downward, resulting in a misalignment with the receiving chamber 32, first ram 120 includes an arm 121 which extends diametrically across the base of the cartridge. Rammer 96 also includes a second ram 122 which depends therefrom forwardly of first ram 120 and in position to engage at the eleven o'clock position the base of cartridge 34 which during the preceding operating cycle had been partially chambered by the first ram, thereby completing the chambering of such cartridge during the forward displacement of the rammer. The forward movements of rammer 96 and operating slide 46 are stopped by the contact of the rammer with the rear face of drum 26 with spring 118 cushioning the impact therebetween. With the forward position of rammer 96 being determined by the rear face of drum 26, the cartridges 34 are not overrammed into drum 26 which would prevent primers of the cartridges being contacted by firing pin 37.

In operation, when cartridge 34 is discharged at the six o'clock position, the discharge gases cause a rearward displacement of operating slide 46 and rammer 96. Through the engagement of cam track 54 in operating slide 46 with the engaged one of the followers 56, drum 26 is rotated one pitch, during the final travel of the operating slide to the recoil position and the initial displacement therefrom, to align succeeding chamber 32 with bore 35 of the barrel 30 at the six o'clock position and move the expended case into registry with case ejection chute 92 for ejection therethrough by an ejector 124 (FIG. 4). Simultaneously, cluster 68 is rotated with drum 26 to move the succeeding cartridge 34 in belt 60 to the one o'clock position in feeding mechanism 22. At the same time, cartridge 34 which had been partially chambered by first ram 120 during the preceding operating cycle is moved to the eleven o'clock position and the previously stripped link 62 is moved therefrom into link ejection chute 88.

Operating springs 52 which were energized during the recoil stroke of operating slide 46 energize the operating slide for the return stroke. During such return stroke, first ram 120 pushes cartridge 34 in the one o'clock position from the associated link 62 and part way into the aligned chamber 32. Simultaneously, second ram 122

contacts the base of cartridge 34 which was partially chambered during the previous cycle and completely chambers it in the aligned chamber as rammer 96 contacts drum 26 to stop forward movement of such rammer. When rammer 96 contacts drum 26, operating slide 46 is resiliently stopped in battery position for discharge of the cartridge chambered at the six o'clock position.

From the foregoing it is clearly apparent that there is provided herein a revolver type machine gun which has many advantages over others provided in the art. These advantages include the symmetrical configuration of housing 58, whereby feed may be changed from one hand to the other without change of housings; the replaceable cover 78, whereby the loading of belt 60 to feeding mechanism 22 is greatly facilitated and the interior thereof is easily accessible in event of any malfunction thereat; the installation of rammer 96 to the cover so as to be removable therewith and so as to be symmetrically disposed relative to the central plane of the feeding mechanism for an even distribution of ramming forces; the disposition of the rammer for contact with the rear face of the drum when in the forward position to prevent an overramming of the chambered cartridge; and the disposition of spring 118 between the rammer and operating slide 46 to cushion the impact thereof when going into battery position and thereby reduce counterrecoil forces in such operating slide.

Although a particular embodiment of the invention has been described in detail herein, it is evident that many variations may be devised within the spirit and scope thereof and the following claims are intended to include such variations.

We claim:

1. In a machine gun including a rotatable drum provided with a plurality of chambers successively indexable at positions relative to the central vertical plane of the gun, the positions including a six o'clock position which coincides with the central vertical plane of the gun at the lower inner section therewith and a one o'clock and an eleven o'clock position disposed above the six o'clock position equidistantly from and on opposite sides of such plane, a feeding mechanism including a housing which is symmetrical in transversal cross-section with an opening in the top to provide easy access to the interior thereof, a cover removably mounted to said housing for covering the opening, sprocket means rotatably disposed in said housing and coupled to said drum for rotation therewith, said sprocket means being adapted to draw a cartridge belt into said housing and to index the cartridges in the belt in alignment with the chambers indexed at the one o'clock and eleven o'clock positions, and a rammer slidably disposed in said cover for contact with the bases of the cartridges indexed by said means at the one o'clock and eleven o'clock positions for a stepped transfer from the cartridge belt into said chambers in such positions.

2. The machine gun as defined in claim 1 wherein said rammer is connected in longitudinal relationship to a reciprocable operating slide for reciprocation therewith and is disposed for contact when in a forward position with the upper segment of the rear face of said drum to prevent an overramming of the cartridges into said chambers and stop said operating slide in a battery position.

3. A machine gun including a recoil mass slidably mounted on the front sections of a pair of rods secured by bracket means to a supporting structure, said recoil mass including a cradle, a drum rotatably supported by said cradle, a plurality of cartridge chambers disposed in said drum so as to be successively indexable at positions relative to the central vertical plane of the gun, said positions including a six o'clock position which coincides with such

plane at the lower intersection therewith and a one o'clock and an eleven o'clock position disposed above the six o'clock position equidistantly from such plane and on opposite sides thereof, an operating slide disposed on said cradle above said drum for reciprocation to and from a battery position responsive to discharge forces, cam means operationally interposed between said operating slide and said drum for converting reciprocation of said operating slide to rotation of said drum, a feeding mechanism mounted on the rear sections of said pair of rods so as to be stationary respective to the supporting structure, said feeding mechanism including a housing which is symmetrical in transversal cross-section for receiving a linked belt with cartridges from either side, an opening in the top of said housing to provide easy access to the interior thereof, a cover removably mounted on said housing for covering said opening, a rammer mounted by rail means to said cover symmetrical to the central vertical plane for longitudinal reciprocation, means for connecting said rammer to said operating slide for reciprocation therewith, and means cooperating with said rammer for transferring the cartridges in a two-step operation from said belt into the chambers indexed at the one and eleven o'clock positions.

25 4. The machine gun as defined in claim 3 wherein said rammer is disposed for contact with the rear face of said drum when said rammer is in the forward position and said operating slide is in battery position and wherein said means for connecting said rammer to said operating slide includes a longitudinally disposed shaft which is connected by pin means to said operating slide, a boss on said rammer provided with a bore to slidably receive said shaft for moveable extension therethrough, a shoulder formed in said bore by a counterbore introduced from the front 30 thereof, an annular flange disposed on said shaft for contact with said shoulder for transferring recoil movement of said operating slide to rearward movement of said rammer, a nut-backed washer mounted on the rear end of said shaft, a spring disposed on said shaft between said 35 boss and said nut-backed washer and preloaded to form a buffer for cushioning the contact between said rammer and drum and reducing the impact forces in said operating slide when going into battery position.

40 5. The machine gun as defined in claim 3 wherein said 45 feeding mechanism includes sprocket means rotatable with said drum for drawing said belt into said housing and for indexing the cartridges in said belt successively at the one and eleven o'clock positions, and wherein said rammer includes a first ram contactable with the base of the cartridge in the one o'clock position for partial transferral thereof from said belt into the aligned one of said chambers during forward movement of said rammer, and a second ram disposed for contact with the base of the partially transferred cartridge at the eleven o'clock position to complete the chambering thereof simultaneously with the partial transferral of the cartridge at the one o'clock position by said first ram.
